CLOSURE CAP AND METHOD OF MAKING
THE SAMEJohn C. Gibbs, Brooklyn, N. Y., assignor to
Anchor Cap & Closure Corporation, Long
Island City, N. Y., a corporation of New York

Application June 4, 1932, Serial No. 615,351

14 Claims. (Cl. 113—121)

The present invention relates to the sealing art, and more particularly to closure caps and a method for assembling the parts thereof.

Screw closure caps having continuous or interrupted thread engaging means are used extensively for sealing various products in containers. The screw threads and lugs in metal caps are visible from the exterior of the package and detract from the appearance thereof, which is particularly objectionable where the packages contain cosmetics or other products purchased chiefly by women. Such packages are required to be attractive in appearance to be commercially salable. Caps composed of thermo-plastic materials have been developed for these packages, but they are much more expensive than metal caps, particularly in the larger sizes. The seal is not as efficient and, due to their fragile nature, there is a large percentage of breakage. The latter is objectionable to the packer, and particularly objectionable to the retailer and the user. If a customer inspecting a package breaks the cap, the retailer does not have caps for replacement, and the package becomes unsalable. Double metal screw caps have been devised to overcome the above difficulties, but they have not been satisfactory. The present invention is an improvement upon these double metal closure caps.

The present invention aims to eliminate the foregoing difficulties and objections by providing a metal closure cap which is attractive in appearance, effective in operation, and which can be manufactured at a low cost. The invention also aims to conceal the threads or container engaging means and to conceal the raw edge of the metal to prevent rust, and to lock the parts securely in position and to prevent relative movement therebetween.

An object of the present invention is to provide a simple, inexpensive closure in which the container engaging means are concealed.

Another object of the invention is to provide an inexpensive metal cap which is attractive in appearance, and particularly useful for application upon fancy or highly decorated packages.

Another object of the invention is to provide a simple, inexpensive, two-piece closure cap adapted to provide a secure seal and, at the same time, conceal the container engaging means.

A further object of the invention is to provide a simple, inexpensive method for assembling and locking the parts of the improved closure.

Other and further objects of the invention will be obvious upon an understanding of the illus-

trative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawing, forming a part of the specification, wherein

Fig. 1 is a side elevational view, partly in section, illustrating a preferred embodiment of the present invention sealed upon a container;

Fig. 2 is an exploded perspective view showing the parts of the closure before they are assembled;

Fig. 3 is a perspective view illustrating the closure in inverted position;

Fig. 4 is an enlarged sectional view of the closure, taken along the line 4—4 of Fig. 3;

Fig. 5 is an enlarged sectional view of the closure, taken along the line 5—5 of Fig. 1;

Fig. 6 is an enlarged sectional view illustrating a slightly different embodiment of the present invention; and

Fig. 7 is an enlarged sectional view illustrating the embodiment of Fig. 6 applied to a continuous thread screw cap.

Referring again to the drawing, and more particularly to Fig. 1, there is shown a container 1 provided with suitable cap engaging threads or lugs 2, substantially adjacent to the mouth thereof, adapted to engage and hold a closure cap 4 upon the container.

The closure cap 4, illustrated in Figs. 1 to 5, preferably comprises an inner cap 5 for engaging the container, and a suitable outer cover cap or shell 6 adapted to be telescoped over the caps and secured thereto. The purpose of the cover cap is to conceal the structural elements of the closure cap and to enhance the appearance of the closure and package. In this manner, a more artistic two-piece cap may be provided without sacrificing the mechanical utility or efficiency of the container engaging means.

In order to accomplish these several objects, the inner cap 5 is preferably in the form of a lug type closure cap, having a cover part 7, and a depending skirt 8, rolled into a wire edge or bead 10 at the lower edge thereof which is thereafter struck radially inwardly at spaced intervals to form lugs or projections 11 adapted to engage the threads 2 of the container. If desired, the central portion or cover part 7 may be cut out. It will be noted that by the formation of

the lugs 11, recesses 12 are provided along the outer periphery of the bead 10. These recesses are utilized for locking the cover cap 6 to the shell 5, as will be described hereafter.

5 Suitable corrugations 14 may be provided in the skirt 9 of the inner cap 5 to facilitate the manufacture of the cap and to assist in holding suitable sealing means within the shell and adjacent to the cover part 7 and also to assist in 10 obtaining a snug fit between the inner cap and outer shell. The sealing means may comprise an impervious disc 15, of oil paper, tin foil or the like, adapted to effect a seal at the mouth of the container, and a compressible disc 16, of material such as cardboard, adapted to serve as a cushion for the disc 15 to hold it resiliently in contact with the container.

The cover cap 6, which is adapted to be telescoped about the inner cap 5 described above, 20 preferably comprises a substantially dome-shaped cover part 17 and a depending skirt 19, of sufficient depth and diameter to receive the skirt 9 of the cap 5. Preferably, the members 5 and 6 are assembled by nesting the shell 5 within 25 the cover cap and then folding the lower edge of the outer skirt 19 radially inwardly so that an inclined or horizontal portion 20 is provided, which engages the wire edge 10 of the inner cap, as shown in Fig. 4. The portions of the skirt 19 of the outer cap, adjacent the recesses 12 and lugs 11 in the inner cap, are pressed further radially inwardly and slightly upwardly to provide projections or depressions 21 in the zone 20 of the outer cap (see Fig. 5). These depressions 30 35 21 extend into the recesses 12 of the cap 5 and lock the inner cap and outer shell to prevent relative rotation or movement thereof. The indentations 21 are not sufficiently deep to mar the appearance of the assembled cap and only fill 40 a portion of the lug recess, so that the resiliency of the lugs is not impaired. A slight depression is sufficient to provide a positive and secure lock between the two parts of the closure. The in-turned edge 20 conceals the raw edge of the 45 outer cap and prevents rust, which would spoil the appearance of the article. The manufacturing operations necessary to form the indentations 21 and inturned edge 20 do not mar the appearance or disrupt the lacquer coating which, to 50 save expense, is applied to the flat sheets of metal from which the caps are made. The inclined or horizontal ledge 20 not only facilitates the assembly of parts 5 and 6 as a unit, but also enhances the appearance of the cap.

55 In Fig. 6, there is illustrated a modification of the present invention, wherein the container engaging cap is assembled within the cover cap by turning the lower portion of the skirt 19 into a wire edge or bead 22. The upper part of the bead portion on the inside of the cap is adapted to abut firmly against the bottom portion of the wire edge 10 of the skirt 9 to hold the members 5 and 6 rigidly in position. In this construction, the raw edge at the bottom of the skirt of the outer cap is completely concealed so that rust is prevented by protecting the raw edge of the cut metal blank.

In Fig. 7, the embodiment of the invention 70 shown in Fig. 6 is shown applied to a continuous thread cap having threads 23 for engaging co-operating threads on a container.

The liners 15 and 16 may be inserted before or after the assembling operation and are then 75 held in position by the lugs 11 and corrugations

14, manually or by means of any suitable machinery.

In the manufacture and assembly of the closure cap 4, illustrated in the preferred embodiment, the inner cap 5 and the cover cap 6 may be formed by the usual manufacturing operations and thereafter loosely assembled by hand or by suitable automatic machinery. It will be noted that after the cover is inserted within the shell, the skirt of the outer cap is slightly longer than 10 the skirt of the inner cap. By presenting the cover and shell, as assembled, to suitable spinning rolls, chucks, or other cap forming mechanism, the lower edge, or protruding portion 20, of the outer skirt 19 is rolled or pressed inwardly to 15 engage the wire edge 10 of the inner skirt 9. As shown in Fig. 5, the recesses 12 formed by the projections 11 permit portions of the zone 20 to be pressed further inwardly to form the projections 21, whereby the shell 5 and the cover 20 cap 6 are locked against relative movement therebetween. Preferably, the lug recesses 12 are only partially filled with the projections 21, whereby the lugs 11 retain their flexibility.

It will be seen that the present invention provides a double closure cap having substantially invisible container engaging means. A cover cap is telescoped about, and locked to, a container engaging inner cap in a simple and effective manner. The inclined ledge 20, or bead 22, further enhances the appearance of the lower edge of the cap and prevents corrosion. By reason of the fact that the material of the cover cap is not subjected to severe mechanical operations, the lacquer is not marred and more artistic designs may be utilized. When the parts of the closure are assembled, they cannot rotate or move with respect to each other. Closures constructed according to the present invention can readily withstand the rough usage to which they may be subjected.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. In a device of the class described, the combination of an inner member having a skirt portion provided with a plurality of spaced inwardly extending container thread engaging means, and an outer cap having a top portion and a skirt portion adapted to receive said inner member, portions of the lower edge of said outer cap skirt being pressed inwardly and upwardly to register and lock with said container thread engaging means on the inner member to prevent relative rotation therebetween.

2. In a device of the class described, the combination of an inner closure cap having a depending skirt provided with a wire edge at the bottom of the skirt and a plurality of spaced lugs formed from said edge, and an outer cover cap 65 having a cover portion and a depending skirt adapted to receive said closure cap, portions of the skirt of said outer cover cap being forced into locking engagement with the recesses formed by said lugs.

3. In a device of the class described, the combination of a cap having a depending skirt provided with a wire edge and inwardly extending thread engaging projections formed in said wire edge, and a second cap having a skirt of greater 75

length and diameter than the skirt of said first cap, the lower edge of the skirt of said second cap being bent inwardly to engage substantially the lower side of the wire edge of said first skirt, 5 and struck inwardly at the projections in the wire edge of said first cap to lock the two caps against relative movement.

4. In a closure cap of the class described, the combination of an inner cap having a skirt portion provided with a plurality of spaced container 10 engaging lugs at the lower edge thereof, and an outer cap having a depending skirt adapted to enclose the inner cap, said depending skirt being bent inwardly beneath the bottom of the inner 15 cap and being forced inwardly and upwardly at the lug to lock with the inner cap.

5. In a closure cap of the class described, the combination of a cap having a depending skirt provided with a wire edge, and inwardly extending 20 container engaging lugs in said wire edge forming recesses, and a second cap having a skirt of greater length and diameter than the skirt of said first cap, the lower edge of the skirt of said second cap being bent upwardly and inwardly 25 at portions to register with and partially fill said lug recesses in said first cap.

6. The method of assembling an outer cover cap and an inner closure cap provided with a plurality of thread engaging lugs forming recesses in the skirt thereof, which method comprises nesting said closure cap within said cover cap, bending the free edge of the skirt of said cover cap into engagement with the lower edge of said closure cap and pressing portions of the 35 free edge of said skirt upwardly into locking engagement with said recesses while said free edge is bent inwardly to engage the lower edge of the inner cap.

7. The method of assembling inner and outer 40 closure caps, said inner cap having a rolled lower edge with symmetrically spaced container engaging lugs therein forming recesses in the exterior of the cap at the bottom thereof, which method comprises inserting the inner cap within 45 the outer cap, bending the lower edge of the outer cap inwardly to envelop the lower edge of the inner cap, and pressing portions of the inwardly bent edge of the outer cap upwardly into the recesses in the inner cap to lock the inner and 50 outer caps relative to each other.

8. In a device of the class described, the combination of an inner member having a substantially cylindrical portion provided at substantially 55 its lower edge with a plurality of spaced radially inwardly extending container thread engaging lugs forming recesses at the lower edge thereof, and an outer cap having a top portion and a skirt portion, the lower edge of the skirt portion of 60 said outer cap being bent upwardly and inwardly at portions to register with the lug recesses in said inner member.

9. In a closure cap of the class described, the

combination of an inner member having a depending skirt provided with a wire edge at its lower edge and inwardly extending container engaging lugs in the wire edge forming recesses, and an outer cap having a substantially smooth cover portion and depending skirt, the lower edge of the depending skirt of said outer cap being bent upwardly and inwardly at portions to register with and partially fill the lug recesses in said inner member. 5

10. In a closure cap of the class described, the combination of an inner member having a skirt portion provided at the lower edge with a plurality of circumferentially spaced radially inwardly extending thread engaging lugs, and an 15 outer cap having a top portion and a depending skirt telescoped over said member, the lower edge of said cap skirt being extended inwardly to engage the lower edge of the skirt portion of said inner member to assemble said member and cap, 20 and portions of the lower edge of said cap skirt being pressed upwardly at said lugs to prevent relative rotation between said inner member and outer cap.

11. A closure including an inner shell and an 25 outer shell, each having a top and a depending skirt, the skirt of the inner shell having threads and an out-curved bead at its lower edge, the skirt of the outer shell being smooth throughout and having a complete in-curved bead on its 30 lower edge, the bead on the outer shell being arranged below the bead on the inner shell and the two opposed convex surfaces of the two beads being in resilient abutting relation.

12. A closure including an inner shell having 35 threads and a bead substantially circular in cross-section, and an outer shell smooth throughout and having a bead substantially circular in cross-section, the second-mentioned bead being below the first-mentioned bead, the two beads being 40 in substantially vertical alignment and the opposed convex surfaces of the two beads being in resilient abutting relation.

13. A closure including an out-curved conventional screw cap with a bead at its lower edge, a 45 shell having a skirt arranged over the screw cap, said skirt being curled inwardly upon itself to form a complete bead below the first-mentioned bead, the oppositely curved surfaces of the two beads being in resilient engagement. 50

14. A closure including an inner shell having a skirt and an outer shell having a skirt, threads formed in the inner skirt, an out-curved bead substantially circular in cross-section at the bottom of the inner skirt, an in-curved bead substantially circular in cross-section at the bottom of the outer skirt below the first-mentioned bead, the oppositely curved surfaces of the two beads being in resilient engagement and the inner side 55 of the lower bead being outwardly of said threads. 60

JOHN C. GIBBS.
